BY *Victor J. Evans*

ATTORNEY

UNITED STATES PATENT OFFICE.

FRANCIS J. ZIPPLER, OF PITTSBURGH, PENNSYLVANIA.

FURNACE CONSTRUCTION.

Application filed September 30, 1925. Serial No. 59,611.

This invention relates to furnaces, and more particularly to cupola furnaces.

One of the main objects of the invention is to provide an improved twyer construction whereby the twyer openings into the furnace may be varied in size and in their relative disposition to suit circumstances and obtain maximum efficiency in operation. A further object is to provide simple and efficient means for supporting the twyer blocks in such manner as to facilitate adjustment hereof. Another object is to insure pre-heating of the air before it enters the furnace, this preheated air being so distributed and controlled as to avoid "freezing" of the metal in the furnace and consequent stoppage thereof. Further objects will appear from the detail description.

In the drawings:

Figure 1 is a vertical sectional view through the lower portion of a furnace constructed in accordance with my invention taken substantially on line 1—1 of Figure 2.

Figure 2 is a section taken substantially on line 2—2 of Figure 1.

Figure 3 is a perspective view of one of the supporting blocks.

Figure 4 is a perspective view of one of the twyer blocks.

Figure 5 is a fragmentary sectional view showing a modified form of construction.

Figure 6 is a modified sectional view showing another modified form of construction.

The furnace A is of known construction and includes a sheathing B which surrounds the refractory material C. The furnace is provided with a neck d which communicates with a throat e discharging into a metal receiving chamber f in the lower portion of the furnace. Furnaces of this type are of well known construction and it is not thought necessary to further describe in detail the construction of the furnace itself.

A flat cast iron ring 1 seats upon the upper face of lower portion f of the furnace and is provided with an upwardly projecting rib 2 remote from its inner edge. Supporting blocks 3 seat upon plate 1, each of these blocks being provided in its lower inner corner with a rabbet 4 which receives rib 2. The block 3 is of approximately T-shape and is provided at its lower end with an outwardly projecting flange 5 which extends to sheathing B, the flange and rib 2 coacting to hold the supporting blocks in position and against movement inwardly of ring 1.

Due to the T-shape of blocks 3, an air receiving space 6 is formed about the furnace in the plane of the blocks. Blocks 3 are spaced apart so as to leave openings 7 for entrance of the air into the furnace, air being supplied to space 6 through openings 8 provided for this purpose in sheathing B, these openings communicating with an air chest or manifold 9 which extends about the furnace and to which air is supplied by means of conduits 10 connected to any suitable or preferred means for supplying air under pressure to the chest.

An upper ring 11 is supported upon blocks 3 and is provided with an inner depending flange 12 which is spaced away from the inner faces of blocks 3 and extends downwardly an appreciable distance from the upper ends of these blocks forming with the inner faces of the blocks an air passage 13. The lower portion of this flange is reduced in thickness from its inner face to form a recess or rabbet 14 which receives projections 15 extending from the upper inner corners of twyer blocks 16 which seat upon the inner portion of ring 1. These twyer blocks are of such breadth as to contact with the inner faces of blocks 3 and extend to the inner edge of plate 1, bridging the space between the two plates. The twyer blocks are spaced apart to provide twyer openings 17 for admitting air into the throat of the furnace. These twyer blocks can be readily adjusted on plate 1 so as to vary the size and relative disposition of the openings to obtain maximum efficiency in operation of the furnace. By having the blocks positioned on end or vertically, and bridging the space between the two plates, these blocks are readily accessible and can be easily adjusted as desired or necessary.

Flues 18 of known construction communicate at their upper ends with the throat of the furnace above the upper plate. These flues also communicate, at their lower ends, with the air space 6 through suitable openings 11^a provided through upper plate 1 and openings 3^a provided through certain of the blocks 3 for this purpose, openings 3^a registering with openings 11^a. As the supporting blocks and associated parts are heated to a high temperature during operation of the furnace, the air which enters space 6 and flows about and between these blocks will be heated to a high temperature before entering the air passage 13 where this

air will be heated to even a higher temperature before being discharged through the twyer openings 17 into the furnace. This insures that the air will be properly pre-heated before entering the furnace and effectually prevents chilling and consequent "freezing" of the metal in the furnace. The admission of this preheated air to the furnace can be controlled by the twyer blocks 18 and as these blocks can be readily adjusted as desired the volume of air admitted to any portion of the throat of the furnace through the twyer openings can be accurately regulated so as to obtain maximum efficiency.

In the modified form illustrated in Figure 5, ring 1^a is provided with two upwardly projecting ribs 2^a between which is seated a lower supporting block 3^b upon which is seated a center ring 2^b. An upper supporting block 3^c is seated on ring 2^b and supports an upper ring 11^b having a depending flange 11^c. The twyer blocks 16^a are supported upon the inner portion of lower ring 1^a each of these blocks being provided with a projection 15^a extending from its upper inner corner in front of plate 2^b, a space 19 being left between the upper end of blocks 16^a and the under face of plate 2^b. Plate 2^b may be continuous or can be formed of spaced segments, as desired. The air flowing between blocks 3^c can pass into the space 13^a between flange 11^c and blocks 3^c so as to be heated, this heated air commingling with the air flowing into space 6 and passing between blocks 3^b. The air which flows between blocks 3^b passes through the spaces between the twyer blocks, some of this air flowing directly into the furnace and the rest of this air flowing through space 19 into the spaces between the twyer blocks and thence into the furnace. The lower supporting blocks 3^b are preferably provided at their outer upper edges with upwardly projecting flanges 3^d which serve to hold the central plate 2^b in position.

In the modified form illustrated in Figure 6 the central plate 2^c is provided with an outer upwardly projecting peripheral flange 2^d which acts to hold the upper supporting blocks 3^e against outward movement, and the depending flange 12 of the upper plate 11 and projection 15^b of twyer block 16^b is rabbeted to receive the reduced lower portion of flange 12 of upper plate 11. The inner portion 2^e of plate 2^c is reduced in thickness to provide a space 19^a between the upper ends of the twyer blocks and the plate. The operation of this modified form is in all essential respects the same as the operation of the form illustrated in Figure 5.

As will be understood, and as hereinabove suggested, changes may be resorted to in the construction and arrangement of parts of the invention without departing from the

field and scope of the same, and I intend to include all such variations, as fall within the scope of the appended claims, in this application in which a preferred form only of my invention is disclosed.

What I claim is:—

1. In a furnace construction, a lower portion, a lower ring seated on said lower portion, supporting blocks seated on the ring in spaced relation, means for supplying air under pressure to the spaces between the blocks, an upper ring seated upon the blocks and having a depending flange spaced away from the inner faces of the blocks, and twyer blocks seated on the lower ring and extending therefrom to the flange of the upper ring, said twyer blocks being spaced apart to provide twyer openings and being independently adjustable upon the lower ring to vary the size and relative disposition of the twyer openings, the upper portion of the furnace resting upon said upper ring.

2. In a furnace construction, a lower portion, a lower ring seated on said lower portion, supporting blocks seated on the ring in spaced relation and provided with outwardly projecting flanges at their lower ends, said blocks being of approximate T-shape, a sheathing forming with the blocks an air space extending about the furnace structure, an upper ring seated on the blocks and having a depending flange cooperating with the upper portions of the block to form an air passage, means for supplying air under pressure to said air space, and twyer blocks mounted on the lower ring inside of the supporting blocks and in spaced relation, said twyer blocks extending from the lower ring to said flange and being independently adjustable upon the ring to vary the size and relative disposition of the twyer openings, the upper portion of the furnace resting upon the upper ring.

3. In a furnace construction, a lower portion, a lower ring seated on said lower portion, supporting blocks seated on the ring in spaced relation and provided with outwardly projecting flanges at their lower ends, said blocks being of approximate T-shape, a sheathing forming with the blocks an air space extending about the furnace structure, an upper ring seated on the blocks and having a depending flange cooperating with the upper portions of the block to form an air passage, means for supplying air under pressure to said air space, the lower ring extending inwardly beyond the supporting blocks, the flange of the upper ring having its lower portion reduced in thickness from its inner face, and a plurality of twyer blocks supported upon the inner portion of the lower ring and independently adjustable thereon, said twyer blocks corresponding in width to the width of the inner portion of the lower ring and being of less height than

the supporting blocks, the twyer blocks being provided at the inner edges of their upper ends with extensions projecting into the lower reduced portion of the flange of the 5 upper ring, the upper portion of the furnace resting upon said upper ring.

4. In a furnace construction, a lower portion, a lower ring seated on said lower portion, supporting blocks seated upon the 10 lower ring in spaced relation, means for supplying air under pressure to the spaces between said blocks, an upper ring seated upon the supporting blocks and having a depending flange spaced away from the inner 15 faces of the blocks, the upper portion of the furnace resting upon said upper ring, the lower ring extending inwardly beyond the supporting blocks, and twyer blocks supported upon the inner portion of the 20 lower ring and extending therefrom to the flange of the upper ring, said twyer blocks being spaced apart and independently adjustable on the lower ring.

5. In a furnace construction, a lower portion, a lower ring seated on said lower portion, supporting blocks seated upon the lower ring in spaced relation and the blocks and the ring being provided with cooperating 30 means for preventing movement of the blocks inwardly of the ring, means for supplying air under pressure to the spaces between said blocks, an upper ring seated upon the supporting blocks and having a depending flange spaced away from the inner faces 35 of the blocks, the upper portion of the furnace resting upon said upper ring, the lower ring extending inwardly beyond the supporting blocks, and twyer blocks supported upon the inner portion of the lower ring and 40 extending therefrom to the flange of the upper ring, said twyer blocks being spaced apart and independently adjustable on the lower ring.

6. In a furnace construction including a 45 sheathing, a lower portion, a lower ring

seated on said lower portion, supporting blocks mounted on the ring in spaced relation and spaced away from the sheathing, means for supplying air under pressure to the space between said blocks and the sheathing, the ring extending inwardly beyond the blocks, an upper ring seated on the blocks and coacting therewith to form an inner air space 50 communicating with the spaces between the blocks, the upper portion of the 55 furnace resting upon the upper plate, and twyer blocks mounted upon the inner portion of the lower ring in spaced relation and bridging the space between the two rings, said twyer blocks being independently 60 adjustable to vary the size and relative disposition of the spaces therebetween.

7. In a furnace construction including a sheathing, a lower portion, a lower ring seated on said lower portion, supporting blocks 65 mounted on the ring in spaced relation and spaced away from the sheathing, means for supplying air under pressure to the space between said blocks and the sheathing, the ring extending inwardly beyond the blocks, 70 an upper ring seated on the blocks and coacting therewith to form an inner air space communicating with the spaces between the blocks, the upper portion of the furnace resting upon the upper plate, twyer blocks 75 mounted upon the inner portion of the lower ring in spaced relation and bridging the space between the two rings, said twyer blocks being independently adjustable to 80 vary the size and relative disposition of the spaces therebetween, and flues communicating with the interior of the furnace above the upper ring, the upper ring and the supporting blocks having openings establishing communication between said flues and the space between the sheathing and said supporting blocks.

In testimony whereof I affix my signature.

FRANCIS J. ZIPPLER.
